UNITED STATES PATENT OFFICE.

ROBERT C. MONTEAGLE, OF WEST NEWTON, MASSACHUSETTS.

STEAM-PISTON.

1,094,461.

Specification of Letters Patent. Patented Apr. 28, 1914.

Application filed May 1, 1913. Serial No. 764,800.

To all whom it may concern:

Be it known that I, ROBERT C. MONTEAGLE, a citizen of the United States, residing at West Newton, in the county of Middlesex and State of Massachusetts, have invented 5 an Improvement in Steam-Pistons, of which the following is a specification.

It is customary to provide steam engine pistons with annular recesses in which 10 spring metal rings are arranged, said rings being split, so that they constantly tend to expand and thus constantly press their bearing surfaces firmly against the walls of the cylinder. As there must be a sliding fit between the sides of one of the rings of this 15 character and the sides of the annular recess in which it is placed, a certain amount of steam will leak between these surfaces, which are next the end of the piston adjacent thereto, and pass into the space between the inner side of the ring and the bottom of the recess, so that the strain tends to press the ring outwardly and thus cause it to be forced against the cylinder wall with greater force than 20 that with which it is normally forced by its spring tension. This tends to cause the ring to bear against the wall of the cylinder with too much force, thereby causing an undue amount of friction and wear. The effect of 25 this outward pressure has been, to an extent, neutralized by the provision of a groove in the middle of the outer face of the ring, and the connection of said groove with the inner side thereof by means of one or more holes, so that the steam which collected between 30 the ring and the bottom of the groove escaped into this groove and the effective pressure on the inner side of the ring was counteracted to an extent corresponding to 35 40 the area of the annular groove.

An object of my invention is to provide a form of ring with which the outward pressure, due to the backing up of steam in the 45 annular groove, will be further reduced and with which the escape of steam about the ring through said groove will be more effectively checked.

It is customary to counterbore the ends of 50 steam cylinders, so that the packing-rings at the ends of the piston will pass over the counterbore to a slight extent, to prevent the wearing of a shoulder at the end of the stroke of the piston, against which the piston would, in time, pound. In centrally 55 grooving the bearing surface of the packing-rings, as above described, the width of said

surface is considerably reduced and a very accurate adjustment of the limits of movement of the piston is necessary to prevent the adjacent bearing surface from passing 60 entirely over the counterbore and yet to cause it to pass thereover to an extent.

A further object of my invention is to provide a construction of packing-ring having the above described characteristics and in 65 which the leeway for adjustment as to the limits of the piston stroke is increased.

I accomplish these objects by the means shown in the accompanying drawing, in 70 which,

Figure 1 is a central cross-section of a steam piston and cylinder made according to my invention. Fig. 2 is a detailed sectional view of the packing-ring. Fig. 3 is an edge view thereof. Fig. 4 is a detailed sectional 75 view of a modification.

According to my invention the cylinder *a* is provided with a piston *b* having an annular groove *c*, therein, adjacent each end, and, as the construction at each end is the 80 same, so far as the present invention is concerned, a description of the construction at one end will suffice. One side of the groove *c* is formed by a head plate *d*, and the surface *d'* thereof, on said plate, is perpendicular to the surface of the piston, and the opposite side, formed by the body of the piston, is slightly inclined toward the end of the cylinder, as it extends outwardly. A split packing-ring *f* is arranged in the groove *c*, 85 said ring being of spring metal and having overlapping ends and a joint breaker *g* to provide a practically continuous ring, as shown in Fig. 3, said construction being well known. The side of the ring next the head 90 plate *d* is perpendicular, and the opposite side is slightly inclined to correspond to the inclination of the side of the groove *c*, so that, as the ring *f* is forced outwardly it will be wedged between the sides of the groove to 95 prevent looseness between said sides, as the contacting surfaces become worn.

According to my invention I arrange the inner surface *f'* of the ring at an acute angle to the side *d'* thereof, so that, when the steam 105 pressure is applied to the inner surface of the ring, instead of having all the pressure on said surface act outwardly, at right angles to the surface of the cylinder, it will have a component longitudinally of the cylinder 110 against the head plate *d*, so that a portion of this outward pressure will be effective in

forcing the ring f more firmly against the plate d , with the result that, with this arrangement, the ingress of steam to the space between the ring and the bottom of the groove will be, to an extent, further prevented.

A series of apertures f^3 are provided in the ring f , which extend from the inner to the outer side thereof, and an annular

- 10 groove f^4 is provided in the outer surface of the ring to which said apertures lead. According to my invention I arrange this annular groove f^4 at one side of the middle of said ring, so that the bearing surface f^5 , between said groove and said face f^2 , is of materially greater width than the surface f^6 at the opposite side of said grooves. With this arrangement I thus provide a relatively wide bearing surface at the steam side of the ring, 15 so that, while the surface which is effective to counterbalance the outward pressure from the chamber at the bottom of the groove in the cylinder, is not reduced, materially, more leeway for adjustment of the stroke of the 20 piston with relation to the counterbore a' of the cylinder, is provided, so that the surface f^5 may be carried over the counterbore at one edge without having it carried completely thereover.

- 30 As shown in Fig. 4, I may provide all the bearing surface of the ring at the steam side thereof, that is, a ring h may be provided having an annular groove h' in its outer surface, which extends from the opposite 35 side thereof from the steam side, providing a relatively wide bearing surface h^2 . However, I consider the arrangement shown in Fig. 1 preferable.

I claim:—

- 40 1. A steam piston having an annular recess adjacent its end adapted to receive steam pressure, a split spring metal packing-ring fitted in said recess and adapted to expand

against the walls of the cylinder, the angle between the side of said ring next the piston end and the inner side of said ring being less than a right angle, to cause the force of the steam-pressure between the ring and the bottom of the recess to have a component to press the ring against the side of the groove 50 next the piston end, substantially as described.

2. A steam piston having an annular recess adjacent its end adapted to receive steam pressure, a split spring metal packing-ring fitted in said recess and adapted to expand against the walls of the cylinder, the side of the recess next the piston end, and the corresponding side of the ring being perpendicular to the outer surface of the ring 60 and the angle between said side of the ring and its bottom being less than a right angle, as and for the purpose set forth.

3. A steam piston having an annular recess, a split, spring-metal packing-ring fitted in said recess and adapted to expand against the walls of the cylinder, said ring having an annular groove formed in its outer surface and an aperture therethrough leading from the inner side thereof to said groove, whereby the bottom of said groove may act as a balancing surface to outward pressure on the inner side of said ring, the portion of said balancing surface at the opposite side of the middle of the ring from 70 the piston end being materially greater than that at the adjacent side, substantially as described.

In testimony whereof, I have signed my name to this specification, in the presence of 80 two subscribing witnesses.

ROBERT C. MONTEAGLE.
